J. H. BOYE.

CURTAIN HANGER.

APPLICATION FILED APR. 17, 1918.

1,288,493.

Patented Dec. 24, 1918.

Inventor:

James H. Boye,

By Pond & Wilson,
Atty's

UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN-HANGER.

1,288,493.

Specification of Letters Patent. Patented Dec. 24, 1918.

Application filed April 17, 1918. Serial No. 228,992.

To all whom it may concern:

Be it known that I, JAMES H. BOYE, a citizen of the United States, residing at Chicago, county of Cook, and State of Illinois, have invented certain new and useful Improvements in Curtain-Hangers, of which the following is a specification.

This invention relates to improvements in devices for suspending curtains, portières and the like, and has for its principal objects to provide, first, an improved rod or pole presenting a desirable combination of strength and lightness, second, an improved device for detachably engaging and supporting the ends of the rod or pole, and, third, in combination with a supporting device an improved means for attaching the usual tip or ornament of the pole. Other objects and advantages of the invention will be apparent to those skilled in the art from a consideration of the following detailed description taken in connection with the accompanying drawing wherein I have illustrated the preferred embodiment of my improved curtain pole together with supporting devices for the ends of the pole, one form of which is adapted to be attached to the inner opposed faces of the window or door frame, and the other form of which, embodying the first named form in respect to the pole engaging part thereof, is adapted to be attached to the front faces of the side members of the window or door frame so as to support the pole in a slightly advanced position relative to the window or door opening.

Referring to the drawings—

Figure 1 is a front elevation, broken out between its ends and partially in section, showing an embodiment of the invention wherein the curtain rod or pole is supported in advance of the window or door opening.

Fig. 2 is a similar view showing an embodiment of the invention wherein the rod or pole is supported in the window or door opening.

Fig. 3 is an inner side elevation of the supporting bracket shown in Fig. 1.

Fig. 4 is a cross-section through the pole.

Fig. 5 is an enlarged fragmentary cross-section, more clearly showing the inwardly pressed seam or joint of the pole.

Fig. 6 is an inner side elevation of the pole supporting device shown in Fig. 2.

Referring to the drawing and considering first the embodiment of the invention illustrated in Figs. 2 and 6, the rod or pole itself is a hollow corrugated metal structure, preferably of brass, and, in the form herein shown, is made in a plurality of telescoping sections so as to be extensible to fit openings of different widths. I have herein shown a central section 10 and end sections 11 telescoping into the ends of the central section. These rod sections have the cross-sectional form illustrated in Fig. 4, and are each made from a corrugated sheet rolled into circular form, with the meeting edges united by an interhooked lap joint best shown in detail at 12 in Fig. 5. It will be observed that this joint lies in the bottom of one of the corrugations and the purpose of this structure is both to give increased strength and rigidity and to prevent separation at the joint. By depressing the joint or seam between two adjacent swells of the corrugated surface, the joint is automatically locked against separation by one of the swells, as will be readily apparent from Fig. 5. So far as I am aware, such an interhooked lap joint in a hollow corrugated rod, pole or pipe that, by reason of being depressed between two adjacent corrugations is self-locking against separation, is broadly new, whether in a curtain pole or other structure and hence, as to this feature, the same is not limited to its use in a curtain rod or pole.

Referring now to the end supporting means, it will be observed that the outer ends of the sections 11 of the pole are formed with vertical slots 13 on their opposite sides. These slots coöperate with end supporting devices, which in the embodiment shown in Figs. 2 and 6 consist simply of plates 14, each having on its lower edge a curved inwardly extended flange 15 on which the lower portion of the end of the rod rests, and on its opposite sides inwardly turned lugs 16 that, as the end of the pole is lowered into position, enter the slots 13 and lock the pole against turning. Each of these plates is provided with a central hole 17 to receive fastening screw 18 by which it

may be readily secured to the inner face of a vertical frame member, such as shown at 19.

In the embodiment of the invention shown in Figs. 1 and 3, I employ the same rod or pole structure as previously described, also the same pole engaging plate 14 with its seat 15 and lugs 16; but in order to support the rod in advance of the window or door opening, I form the plate 14 on the outer end of 10 a supporting bracket 20 that has a base flange 21 adapted to be secured by screws 22 to the outer faces of the frame members 19. The plate 14 and bracket 20 with its flange 21 are preferably made integral, being cut 15 and pressed to shape from a suitable sheet metal blank. Rods or poles thus supported to one side of the opening are commonly provided with end tips or ornaments in the form of balls, cones or the like; and I have 20 herein shown such ornaments at 23 in Fig. 1, of hollow sheet metal form. To provide for a simple and efficient attaching means for these ornaments I form on the outer sides of the pole supporting plates 14 outwardly pressed and centrally apertured 25 bosses 24 through each of which is entered a drawn neck 25 on the ornament 23, the inner edge of the neck being swaged down against the inner side of the boss 24 to 30 make a rigid and permanent fastening. In this construction it will be seen that the pole or rod proper may readily be removed from and applied to its support without disturbing the end tips or ornaments which are carried by the brackets.

It is believed that the structure, mode of use, and advantages of the invention will be readily understood and appreciated from the foregoing, without further detailed description. Manifestly, the structure may be modified in respect to details without altering 40 its substantial character or sacrificing the advantages inherent therein, hence I reserve all such variations and modifications

as fall within the spirit and purview of the 45 invention as defined in the appended claims.

I claim:

1. A hollow corrugated metal rod or pole having an interhooked lap joint located in the depression between two adjacent corrugations, whereby the interhooked members 50 of the joint are locked against separation.

2. As an article of manufacture, a support for the end of a curtain rod or pole consisting of a plate formed with a substantially 55 central aperture and provided on its pole-engaging side with means for supporting the pole and locking the same against rotation.

3. As an article of manufacture, a support for the end of a curtain rod or pole consisting of a plate having on its inner side 60 means for holding the pole against rotation and on its outer side a centrally apertured projecting boss adapted to receive the stem or neck of an end tip or ornament. 65

4. As an article of manufacture, an integral or one-piece supporting bracket for a curtain pole consisting of an arm having at one end an attaching flange and at its other end a plate, said plate being formed on its pole-engaging side with means for supporting the pole and locking the same against rotation and also being formed with a substantially central aperture adapted to be entered by the stem of an end tip or ornament. 70

5. A supporting bracket for a curtain pole provided with means for attachment to a window or door frame and formed at its outer end with a plate having on its inner side means to engage an end of the pole and 80 support the same and lock it against rotation, and having on its outer side a hollow centrally apertured boss, in combination with an end tip or ornament having a neck or stem engaged and interlocked with the 85 hollow boss of said bracket plate.

JAMES H. BOYE.
